MAGNETIC SEPARATOR

Samuel G. Frantz, Princeton, N. J.

Application August 4, 1941, Serial No. 405,331

6 Claims. (Cl. 209—224)

This invention relates to magnetic separators, and although not restricted to such use is particularly effective in removing iron and iron-bearing particles of fairly high magnetic susceptibility from a free-flowing stream of dry materials.

An instance of such use is the placing sand used in the saggers in which glass and pottery ware is fired. Where such sand is exposed to iron contamination, surface spots of iron and iron-bearing particles form on the fired ware and have to be subsequently removed by mechanical means.

These spot-forming particles occur in the sand as an impurity and represent only a very small percentage of the total sand, but it is essential that any separator for removing them magnetically from the sand or other grain stream shall be of high capacity and high efficiency.

My separator has these characteristics to an unusual degree, and is moreover of low initial cost and low operating cost.

In constructing my separator, I utilize the general principle of the screen type wet separator disclosed in my prior Patent No. 2,074,085, granted March 16, 1937, but in place of the stack of magnetized attractor screens shown in said patent, I employ a stack of magnetized vanes in the form of grids. The vanes of one grid are inclined in opposite direction to those of the grids next above and below in the stack. This causes the sand or other free-flowing material to repeatedly change direction as it falls from top to bottom of the stack, thus limiting the velocity of the stream and affording the magnetized edges of the vanes ample opportunity to attract and hold any magnetically susceptible particles in the stream.

The greatest concentration of magnetic attraction is at the sharpened upper and lower edges of the vanes, and inasmuch as these edges are very closely placed to the zones where the sand stream is changing direction and hence moving most slowly, there is little or no danger that the magnetic particles will be carried past said highly magnetized edges without being caught and held thereby.

In the accompanying drawing:

Fig. 1 is a vertical central section through a magnetic separator in accordance with my present invention.

Fig. 2 is a top plan view of one of the attractor grids removed from the stack, and

Fig. 3 is a diagram illustrating the action of my separator.

My improved magnetic separator comprises a

coil case including a housing or shell 10 and top and bottom plates 11 and 12. Fastened to the top plate 11 is a feed bowl or hopper 13. The bottom plate 12 is fastened to a suitable supporting base 14. The shell 10, plates 11 and 12, hopper 13, and base 14 are made of iron, steel or other suitable magnetizable material to provide a magnetic circuit.

Mounted within the shell 10 and spaced therefrom is a cylinder 15 of brass or other non-magnetizable material. In the space between the shell 10 and cylinder 15 is a coil 16 adapted to be connected to any suitable source of direct electric current.

Removably mounted within the cylinder 15 so as to be magnetized by the coil 16 is a vertical stack of attractor units 17 of magnetizable material. These are constructed as grids each comprising an annular ring 18 and a plurality of uniformly spaced and suitably reinforced vanes 19 integral with said ring and all inclined in the same direction. The vanes are sharp at their upper and lower edges to provide the maximum concentration of magnetic flux, and are thickened between said edges both for strength and to reduce the magnetic reluctance.

The several grids are suitably spaced from one another in the stack of spacers 20 of non-magnetic material.

At each end of the stack is a spider 21 and 22, or its equivalent, made of magnetizable material. The purposes of these spiders is to carry the magnetic flux from the ends of the shell 10 and distribute it efficiently over the endmost grids of the stack, thereby reducing the reluctance of the magnetic circuit and increasing the magnetization of the grids.

The grids are so positioned within the cylinder 15 that the vanes of one grid extend in opposite direction to the vanes of the grids immediately above and below. Any number of grids may be employed, depending upon the size of the separator, and preferably, the vanes of each grid are inclined at an angle of 45° so that the stream will change its direction of motion by approximately 90° in passing through each two adjacent grids, although this angle may obviously be varied as desired.

In operation, sand or other free-flowing material containing iron or other magnetically susceptible impurities is fed into the hopper 13 and falls by gravity through the stack of grids 17.

Due to the reversely inclined arrangement of the vanes in the several grids composing the stack the velocity of the streams is reduced to

the point where the particles are slowly sliding and rolling rather than freely falling as they change direction at each successive grid. In the region of these direction changes, that is to say, at the upper and lower edges of the vanes in any grid, the magnetic field strength and convergence is strongest and consequently the particles of iron or other magnetically susceptible contamination in the stream are attracted to and held by said edges.

At suitable intervals the current is turned off, thereby demagnetizing the attractors, so that the accumulated contaminations may drop by gravity from their edges. When more thorough cleaning is desirable, the stack of attractors may be removed from the machine and mechanically cleaned.

Although I have discussed my invention in connection with the removal of magnetically susceptible contaminations from a free-flowing grain stream, it will be understood that such discussion is illustrative and not limiting. It will likewise be understood that various modifications in the construction and arrangement of the grids may be made, depending upon the type of material being separated, and the degree of separation wanted.

What I therefore claim and desire to secure by Letters Patent is:

1. A magnetic separator for removing magnetically susceptible particles from a stream, comprising a stack of superposed spaced magnetized attractors, each attractor comprising a relatively narrow rim and a plurality of spaced vanes extending longitudinally within the inner periphery of said rim and secured at their ends to said rim, said vanes being inclined transversely of their length, the attractors being horizontally positioned in the stack with the vanes of one attractor inclined oppositely to those of the attractors above and below it so as to reduce the velocity of the stream by causing it to change direction at each attractor and the upper and lower edges of the vanes of each attractor being located at the regions where the stream is changing direction and hence moving most slowly, and means for producing concentrations of magnetic flux upon the upper and lower edges of said vanes whereby magnetically susceptible particles in the stream are attracted to and held by said edges.

2. The separator of claim 1, the upper and lower edges of the vanes being sharpened to increase the concentration of magnetic flux thereon, and the bodies of the vanes being thickened to decrease their magnetic reluctance.

3. The separator of claim 1, the rim of each attractor being of less depth than the overall depth of said attractor through the vanes, and spacing rings of the same shape as said rim, each ring being of non-magnetic material and being of a depth to space the upper and lower edges of the vanes of adjacent attractors out of contact with each other.

4. A magnetic separator for removing magnetically susceptible particles from a stream, comprising spaced concentric inner and outer shells, one of magnetizable material and the other

of non-magnetizable material, a support for said shells and a feed hopper supported by said shells, a winding in the space between said shells, and a stack of superposed spaced magnetized attractors within said inner shell, each attractor comprising a rim and spaced inclined vanes, and the attractors being horizontally positioned in the stack with the vanes of one attractor inclined oppositely to those of the attractors above and below it so as to reduce the velocity of the stream by causing it to change direction at each attractor, the upper and lower edges of the vanes of each attractor being located at the regions where the stream is changing direction and hence moving most slowly, and being formed to produce concentrations of the magnetic flux so that magnetically susceptible particles in the stream are attracted to and held by said edges.

5. An attractor to be placed horizontally across the path of a stream passing through a magnetic separator, said attractor being formed of magnetizable material and comprising a relatively narrow rim and a plurality of spaced vanes extending longitudinally within the inner periphery of said rim and secured at their ends to said rim, said vanes being inclined transversely of their length the upper and lower edges of said vanes being formed to produce concentrations of the magnetic flux whereby magnetically susceptible particles in the stream are attracted to and held by said edges.

6. A magnetic separator for removing magnetically susceptible particles from a stream, comprising a supporting base and an outer cylindrical shell surmounting said base, both said base and shell being of magnetizable material to provide a magnetic circuit, a hopper surmounting said shell for directing a flow stream therethrough, an inner cylindrical shell of non-magnetizable material and of less diameter than said outer shell mounted within said outer shell and defining therewith an annular space to receive a coil, a coil in said space to be connected with a source of electric current, and a stack of spaced superposed attractor units of magnetizable material removably mounted within said inner shell, said units being in the form of horizontally disposed grids and each grid comprising an annular ring, and a plurality of spaced vanes integral with said ring, all vanes of each ring being inclined in the same direction and the grids being so arranged in the stack that the vanes of one grid are reversed to the vanes of the grids next above and below so as to reduce the velocity of the flow stream by causing it repeatedly to change direction as it passes through said stack, the upper and lower edges of the vanes of each grid being sharpened to create the maximum concentration of flux at said edges and said edges being located at the regions where the stream is changing direction and hence moving more slowly, and spliders of magnetizable material at the ends of the stack for carrying the magnetic flux from the ends of the outer shell to the endmost grids of the stack.
